Primary Examiner—Charles A. Rademaker*(74) Attorney, Agent, or Firm*—Finnegan, Henderson, Farabow, Garrett, & Dunner, L.L.P.(57) **CLAIM**

The ornamental design for a capsule, as shown and described.

DESCRIPTION

FIG. 1 is a perspective view of a capsule showing our new design;

FIG. 2 is a bottom plan view thereof;

FIG. 3 is a top plan view thereof;

FIG. 4 is a side elevation thereof;

FIG. 5 is a side elevation of the side opposite that shown in FIG. 4;

FIG. 6 is a perspective view of a modified embodiment of the design shown in FIGS. 1 through 5;

FIG. 7 is a bottom plan view thereof;

FIG. 8 is a top plan view thereof;

FIG. 9 is a side elevation thereof; and,

FIG. 10 is a side elevation of the side opposite that shown in FIG. 9.
